UNITED STATES PATENT OFFICE.

HENRY F. GOETZ, OF WATERBURY, CONNECTICUT, ASSIGNOR TO WATERBURY M'F'G CO., OF WATERBURY, CONNECTICUT, A CORPORATION.

DESIGN FOR AN OVERFLOW AND WASTE FIXTURE.

52,040.

Specification for Design.

Patented May 14, 1918.

Application filed January 19, 1918. Serial No. 212,847. Term of patent 14 years.

To all whom it may concern:

Be it known that I, HENRY F. GOETZ, a citizen of the United States, residing at Waterbury, in the county of New Haven and State of Connecticut, have invented a new, original, and ornamental Design for an Overflow and Waste Fixture, of which the following is a specification, reference being had to the accompanying drawing, forming part thereof.

The figure is a side view of an overflow and waste fixture, showing my new design.

I claim:

The ornamental design for an overflow and waste fixture, as shown.

HENRY F. GOETZ.
